UNITED STATES PATENT OFFICE.

JOHN H. BURCH, OF CLAY, MISSISSIPPI.

CHURN.

1,035,685.

Specification of Letters Patent. Patented Aug. 13, 1912.

Application filed October 16, 1911. Serial No. 654,915.

To all whom it may concern:

Be it known that I, JOHN H. BURCH, a citizen of the United States, residing at Clay, in the county of Itawamba and State 5 of Mississippi, have invented certain new and useful Improvements in Churns; and I do hereby declare the following to be a full, clear, and exact description of the invention, such as will enable others skilled in the 10 art to which it appertains to make and use the same.

This invention relates to churns, and is designed to provide a mechanism whereby the churn may be actuated for the usual 15 purposes, and at the same time construct said mechanism in such a manner that it is applicable to churns of all sizes and shapes.

Heretofore in the driving mechanism for churns it has been customary to manufacture and permanently attach the same to the barrel or receptacle of the churn. This 20 has been found to be very objectionable by reason of the fact that the driving mechanism often breaks and necessitates the buying of an entirely new machine.

It is the object of the present invention to provide a driving mechanism, the elements of which may readily be replaced and at the same time be applicable to any suitable 25 receptacle, whether the same be constructed to conform with the driving mechanism, or not.

With the above and other objects in view, this invention consists in the construction, 30 combination and arrangement of parts, all as hereinafter more particularly described, claimed and illustrated in the accompanying drawings, wherein:

Figure 1 is a central, vertical section of 35 a churn constructed in accordance with the present invention; Fig. 2 is a side elevation thereof; Fig. 3 is a section taken along line 3—3 of Fig. 2; and Fig. 4 is a section taken along line 4—4 of Fig. 2.

The churn forming the subject matter of 40 the present invention comprises a platform supported by a plurality of telescopic, adjustable legs which are arranged at an obtuse angle to the said platform, and at an 45 acute angle to the ground. A plurality of transversely arranged crosses braces or supports are removably and rigidly secured to the said legs. Upon each section of these 50 supports is slidably mounted a clamp which is retained on said bars or supports in various 55 positions by set screws operating

through said clamps and engaging said members or supports. These clamps are adjustable and will engage the bottom of any suitable receptacle, whether the same be 60 round or square, or even elliptical, and retain the same rigidly while the churn plunger or dasher is operating therein. A bearing or bracket is mounted upon the upper surface of the platform, and is provided 65 with a gear mechanism actuated by a handle which operates a pitman, this pitman operating a reciprocatory rod to which is adjustably attached a dasher, said dasher operating below the under surface of the 70 platform, and is adapted to be projected into a receptacle or tub for the purpose of creating action therein to produce butter.

Reference being had more particularly to the drawings, 10 indicates a platform having a plurality of legs 11 secured thereto, said legs constituting a plurality of rods 11^a, adapted to be received in the tubular bars 11^b and are retained in various positions therein through the instrumentality 75 of the set screws 11^c. A bar 12 is interposed between each pair of tubular sections 11^b, said bars being notched for the purpose of crossing the same as at 13, in order that the upper edges thereof may rest in a horizontal plane. A clamp 14 is slidable on each half of each bar 12, said clamp being retained in various positions upon said bar by the set screw 15. These clamps are so 80 adjustable that the same will engage and 90 rigidly secure any suitable receptacle or tub 16 upon the supports 12, as illustrated 85 in the drawings.

A bracket 17 is mounted upon a platform 95 10 and is provided with a transverse extension 18 at the upper terminal thereof, in which operates a tubular rod 19 connected to a pitman 20, which likewise operates in a slot 22 of the extension 18 through the instrumentality of a joint 21. A crank shaft 100 23 is mounted in the bracket 17 and operates a gear 24. A shaft 25 is mounted in the bracket 17 directly below the crank shaft 23, and is driven from the said crank shaft 23 by the gear 26 mounted on the shaft 25 and 105 meshing with the gear 24 of the crank shaft 23. A pair of balance wheels 27 are mounted on the shaft 25, one of said wheels being mounted within the bracket, and the opposite balance wheel being mounted without 110 the bracket. The balance wheel 27 located upon the exterior of the bracket is suitably

connected to the pitman 20. Thus, it will be seen that upon operating the crank shaft, the tubular reciprocating rod will be operated, thereby imparting a similar motion 5 to the dasher 28 extending through the platform 10 and adjustably secured in the tubular rod 19 by the set screw 29. This dasher carries any suitable blade 30 at the lower terminal thereof for the purpose of operating upon the cream.

Having thus fully described my invention, what I claim as new and desire to secure by U. S. Letters Patent, is:

1. In a device of the character described, 15 a platform provided with outwardly inclined telescopic legs, a churn body mounted beneath the platform, a bracket mounted on the platform, a train of gear wheels supported by the bracket, a pair of balance 20 wheels in train with the wheels, a pitman eccentrically pivoted on one of the balance wheels, an extensible churn dasher shaft pivoted to the pitman, and a crank mounted on one of the train of wheels for driving the 25 same and reciprocating the dasher within the churn body.

2. In a device of the character described, 30 the combination of a platform provided with outwardly inclined telescopic legs, horizontal bars crossing each other angularly secured to the several pairs of oppositely disposed legs, a churn body mounted on the bars, clamps on the several bars adapted to

secure the churn body centrally and vertically beneath the platform, and means for 35 mechanically reciprocating a churn dasher in said churn.

3. In a device of the character described, the combination of a platform provided with outwardly inclined telescopic tubular 40 legs, of horizontal bars crossing each other angularly and secured to several pairs of oppositely disposed legs, a churn body mounted on the bars, clamps adapted to be secured to the several bars and to engage the 45 churn body to hold the same centrally and vertically beneath the platform, a bracket mounted on the platform, a gear mechanism mounted on the bracket, a pair of balance wheels connected to the gear wheels, a laterally extending arm at the other terminal of the bracket, a pitman pivotally secured eccentrically of one of the balance wheels, a tubular rod pivotally secured to the free 50 terminal of said pitman, a churn dasher 55 having a rod secured thereto, said dasher rod being adjustably mounted in the tubular rod aforesaid, and means to actuate the gear mechanism and to reciprocate the churn dasher.

In testimony whereof I affix my signature in presence of two witnesses.

JOHN H. BURCH.
